United States Patent

Des. 234,662
Patented Apr. 1, 1975

234,662

TABLE

Frank Joseph Stiene, Ridgewood, N.J., assignor to Mercedes-Benz of North America, Inc., Montvale, N.J.

Filed Aug. 21, 1972, Ser. No. 282,574

Term of patent 14 years

Int. Cl. D6—03

U.S. Cl. D6—177

FIG.1

FIG.2

FIG.3

FIG.4

FIG.5

FIG.6

FIG. 1 is an oblique perspective view from in front and above, of a table embodying my novel design;

FIG. 2 is a side view of the table of FIG. 1;

FIG. 3 is a front view of the table of FIG. 1;

FIG. 4 is a rear view of the table of FIG. 1;

FIG. 5 is a top view of the table of FIG. 1; and

FIG. 6 is a bottom view of the table of FIG. 1.

I claim:

The ornamental design for a table, as shown and described.
